SASH LOCK

Charles A. Pressnall, Elkhart, Ind., assignor to the
Adlake Company, Chicago, Ill., a corporation
of Illinois

Application December 26, 1942, Serial No. 470,170

6 Claims. (Cl. 292—204)

This invention has to do with windows of the type having upper and lower sash, one of which is vertically slidable with respect to the other to open the window, and is particularly concerned with the locking means employed for preventing the window from being opened from the outside.

The locking means heretofore employed for this purpose have ordinarily been mounted on the meeting rails of the sash, in a conspicuous and obstructive position, and have been rather costly to manufacture and install.

The object of the present invention is to provide an improved form of sash lock which is exceedingly inexpensive to manufacture and install, is pleasing in appearance, is inconspicuously located, and instead of being mounted on the meeting rails is carried entirely by the removable glazing bead associated with one of the side rails of the upper sash.

While the foregoing statements are indicative in a general way of the nature of the invention, other more specific objects and advantages will be apparent to those skilled in the art upon a full understanding of the construction, arrangement and operation of the improved sash lock.

A preferred embodiment of the invention is presented herein by way of exemplification, but it will of course be appreciated that the invention is susceptible of incorporation in other structurally modified forms coming equally within the spirit of the invention and the scope of the appended claims.

In the accompanying drawing:

Fig. 1 is a fragmentary perspective view of a double-hung window equipped with the improved sash lock;

Fig. 2 is a fragmentary face view of the corner of the upper sash in which the lock is located, showing the lock in its operative position;

Fig. 3 is a vertical section, taken on the line 3—3 of Fig. 2;

Fig. 4 is a side view of the one-piece locking member, removed from the glazing bead;

Fig. 5 is a top view of the locking member; and

Fig. 6 is a side view of the leaf spring used with the locking member.

The drawing shows a double-hung window having a vertically slidable upper sash 10 and a vertically slidable lower sash 11. The side rails 12 of the upper sash 10 are provided on their inner sides with hollow glazing beads 13 which are detachably secured to the side rails by screws 14.

The improved locking means—which may be located at either or both sides of the upper sash—

is a small one-piece member which is characterized by a vertically extending stem portion 15, a horizontally projecting nose portion 16 at the base of the stem portion, and a vertically extending handle portion 17 above the free end of the nose portion.

This locking member may be quickly applied to the window, ready for use, by merely removing one of the beads 13, cutting off or notching out 10 a short section from the lower end of the bead corresponding to the height of the nose portion 16 at the base of the stem portion 15, placing the stem portion 15 in the opening in the lower end of the bead, along with a small slightly bowed leaf spring 18, and replacing the bead.

The stem portion 15 is of generally cylindrical form and is slightly smaller than the hollow interior of the bead, in order to turn freely but snugly in the same, and is flattened on two surfaces 19 and 20 at right angles to each other whereby to be engaged and yieldingly held against turning by the spring 18. The spring 18 tends to hold the stem portion 15 with the free end of the nose portion 16 either (1) projecting at right angles to the plane of the sash in a position overlying the upper surface of the meeting rail 21 of the lower sash (as shown in full lines in Fig. 1) or (2) projecting sidewise in an out-of-the-way position over the upper surface of the meeting rail 22 of the upper sash (as shown in dot-dash lines in Fig. 1). The spring 18, disposed alongside the stem portion 15, is held against turning with the stem portion by reason of its engagement with interfitting surfaces on the inside of 35 the bead.

The lock may be located immediately above the upper surface of the meeting rail 21 of the lower sash, as shown in the drawing; or it may be located any desired distance above said upper 40 surface, to permit the window to be opened a limited amount for ventilation with the lock in its operative position; or two of the locks may be employed, in both of the above described locations. When it is desired to locate the lock in 45 vertically spaced relation to the upper surface of the meeting rail 21 of the lower sash, the glazing bead is cut in two at the proper height and a short section removed to accommodate the base of the nose portion 16, after which both 50 parts of the bead are replaced, with the stem portion 15 of the lock telescoped within the upper part. When the lock is used in such an intermediate position, it may be provided, if desired, with an additional downwardly extending stem portion, similar to and in axial alignment with

the upwardly extending stem portion 15, for insertion within the upper end of the part of the beading directly beneath the same.

While the lock is illustrated in the drawing as applied to a window of the well known double-hung type—in which the upper sash as well as the lower sash is vertically movable—it will of course be appreciated that the lock is equally applicable to a window in which the upper sash is fixed and the lower sash movable, or vice versa, and also in which several sash are present, one above the other, with one or more of the sash fixed and the remaining movable, or all movable.

I claim:

1. In a window of the type having an upper sash and a vertically movable lower sash, a glazing bead removably associated with one of the side rails of the upper sash on the inside of the latter, and a locking member carried by the bead for abutment with the top rail of the lower sash, said locking member having a vertically extending stem portion which is pivotally mounted in a vertically elongated recess in the bead, and having a horizontally extending nose portion which is rotatable about the axis of the stem portion from a locking position substantially at right angles to the plane of the sash to an inoperative position substantially parallel to such plane.
2. In a window of the type having an upper sash and a vertically movable lower sash, a glazing bead removably associated with one of the side rails of the upper sash on the inside of the latter, and a locking member carried by the bead for abutment with the top rail of the lower sash, said locking member having a vertically extending stem portion which is pivotally mounted in a vertically elongated recess in the bead, and having a horizontally extending nose portion which is rotatable about the axis of the stem portion from a locking position substantially at right angles to the plane of the sash to an inoperative position substantially parallel to such plane, said nose portion being extended upwardly exteriorly of the bead to provide a wing-like finger piece for use in moving the nose portion.
3. In a window of the type having an upper sash and a vertically movable lower sash, a hollow glazing bead removably associated with one of the side rails of the upper sash on the inside of the latter, and a locking member carried by the bead for abutment with the top rail of the lower sash, said locking member having an upwardly extending stem portion which is pivotally mount-

ed in the lower open end of the hollow bead, and having a horizontally extending nose portion which is rotatable about the axis of the stem portion from a locking position substantially at right angles to the plane of the sash to an inoperative position substantially parallel to such plane, said stem portion being of generally cylindrical form and being provided with one or more flattened areas, and a bowed leaf spring positioned in the end of the bead alongside the stem portion for indexing engagement with the flat area or areas for holding the lock in either its locking position or its inoperative position.

4. In a window of the type having an upper sash and a vertically movable lower sash, a glazing bead removably associated with one of the side rails of the upper sash on the inside of the latter, and a locking member which is rotatable about the longitudinal axis of the bead and is provided with a journaling portion which is telescopically associated with the bead, said locking member also having a radially projecting portion which when turned into one position is adapted to abut with the top rail of the lower sash.
5. In a window of the type having an upper sash and a vertically movable lower sash, a glazing bead removably associated with one of the side rails of the upper sash on the inside of the latter, and a locking member associated with the glazing bead, said locking member having a mounting portion which is telescopically associated with a portion of the bead within the contour of the latter, and said locking member having a portion which projects laterally from the mounting portion for engagement with the top rail of the lower sash to prevent the window from being opened.
6. In a window having upper and lower sash, one of which is vertically slidable with respect to the other, the combination with a glazing bead removably associated with one of the side rails of one of the sash on the inside of the latter of a locking member carried by the glazing bead, one end of said bead terminating short of the corresponding end of said side rail, whereby to provide a gap between that end of said bead and the corresponding end of the side rail, and a locking member positioned in said gap and rotatably connected with said bead, said locking member being provided with a projecting portion for abutment with the other sash.

CHARLES A. PRESSNALL.
